UNITED STATES PATENT OFFICE

2,504,757

DART

Robert S. Terry, Indianapolis, Ind.

Application October 17, 1947, Serial No. 780,465

5 Claims. (Cl. 273—106.5)

1

The present invention relates to projectiles of the type adapted to be propelled manually or by means of an elastic member or a bow string and such missiles are often referred to as darts. The invention more specifically pertains to the shape or design of the body of the dart so as to provide a missile that will more truly adhere to a projected line of flight.

It is an object of the invention to provide a dart with a relatively long or elongated groove in the aft portion thereof so as to reduce the weight of the rear end of the projectile and to shift the center of gravity forwardly whereby the flight of the projectile will be stabilized by concentrating the major portions of the weight towards the forward end of the projectile.

Another object of the invention is to provide a groove or slot in the rear portion of a dart having a greater width in the rear end thereof than the width of the slot at the forward end so as to further reduce the weight of the aft portion and at the same time to provide a slot of increasing width proceeding rearwardly of the missile to permit the dart to more readily escape an elastic band or bow string in firing the projectile.

A further and more detailed object of the invention resides in providing a dart with one or more fins arranged outwardly of the relatively long arms formed by the groove or slot, so as to stabilize the dart in flight and prevent wavering or wobbling of the lightened aft portion of the missile during a projected flight towards a target.

Other objects and features of the invention will be more apparent as the present disclosure proceeds and upon consideration of the accompanying drawing and the following detailed description wherein several typical embodiments of the invention are disclosed.

In the drawings:

Fig. 1 is a perspective view of a dart exhibiting the invention.

Fig. 2 is a side elevational view of the projectile shown in Fig. 1.

Fig. 3 is a front elevational view.

Fig. 4 is a front elevational view illustrating a modification.

Fig. 5 is an end elevational view illustrating a further modification.

The invention pertains to a dart of the type which may be hurled forwardly by the hand of an individual towards a target and thereby forming an implement for use in a target game which may be played indoors or outside a building. The

2

dart is also of the type which may be propelled forwardly towards a target by means of an elastic member or by means of a bow string such as is employed for propelling an arrow. A characteristic feature of the invention pertains to a groove or slot extending lengthwise of the dart throughout the major portions of the length, and this groove provides the advantage of reducing the weight of the aft portion of the missile and thereby concentrating the weight near the forward end. Such shifting of the center of gravity provides a projectile which is stable in flight. The elongated groove also facilitates the adaptation of the projectile to a bow string or an elastic member employed in projecting the dart forwardly. A more detailed feature pertains to the progressive widening of the slot in proceeding rearwardly of the projectile.

Referring to the drawing, there is shown at 10 a body portion of a projectile which may be formed of wood or any suitable lightweight material such as plastic or even a light weight metal alloy. The nose portion carries a pin or elongated metal member 12 provided with a sharp and pointed end 14 for penetrating the target such as a relatively soft board having a target design thereon. The pin 12 may be embedded in the nose portion as is indicated in dotted lines of Fig. 2, and securely anchored therein so as to be rigidly attached to the dart body and at the same time maintained in alignment with the longitudinal axis of the dart.

The nose portion of the projectile slopes rearwardly and outwardly from the pin 12 so as to provide a profile which is so shaped as to reduce aerodynamic resistance to the forward movement of the dart. It is to be noted that the projectile is circular in shape rearwardly of the nose, as clearly shown in Fig. 3 and may be provided with a diameter rearwardly of the point 16 which is somewhat smaller than the maximum diameter of the nose portion.

In one exemplary embodiment, the overall length from the nose 18 to the rear end amounts to approximately three and one-half inches. A characteristic feature of the invention however pertains to the length of a slot or groove 21 which is arranged to extend lengthwise of the axis of the dart. This groove is of such length as to extend forwardly from the rear end approximately two and one-half inches when the overall length of the dart body amounts to three and one-half inches. Accordingly, in carrying out the invention, the length of the groove 21

represents approximately two-thirds of the length of the projectile body.

The creation of this groove removes a considerable portion of the material forming the body of the projectile, and accordingly reduces the mass of the aft portion. The center of gravity of the projectile is thereby shifted forwardly and lies somewhere in front of the forward termination of the groove 21. This concentrates the weight of the projectile forwardly and tends to stabilize the flight of the missile. 10

Another feature of the device pertains to the shape of the groove 21, which is wider between the rear tip portions of the arms 22 than at the forward end 24. This progressive widening of 15 the groove in proceeding rearwardly tends to further diminish the weight of the aft portion of the projectile, and at the same time provides a groove having walls which progressively diverge from each other so as to permit the dart to escape 20 from a bow string or the like without engaging such a propelling element.

A dart embodying the invention includes one or more fins as shown in Figs. 1 to 3, where two fins 26 and 27 are employed to further stabilize the projectile in its movement towards the target. These fins may be formed of any light weight sheet material such as cellulose acetate or any other plastic or cardboard. The fins are desirably seated in grooves in the outer periphery of the dart. One of such grooves is indicated in dotted lines at 28 in Fig. 2. When two fins are employed, they are preferably arranged in diametrically opposite position as shown in Fig. 3.

A modification includes more than two fins, and in another example as shown in Fig. 4, a larger number of fins are employed. In this embodiment four fins 31, 32, 33 and 34 are mounted in radially arranged planes on the projectile. When a number of fins greater in number than two are employed, these fins may be circumferentially spaced so as to radiate from the arms 22 defining the groove 21. The dart shown in Fig. 4 is adaptable for outdoor use where air currents have a greater tendency to influence the flight of the projectile towards the target. 35

The concentration of the weight at the forward end portion tends to maintain the missile in a true and stabilized flight towards the target. If a bow string or elastic member is employed for urging the dart forwardly, this element may be introduced into the slot or groove 21 so as to engage the projectile adjacent the forward end 24 of the slot. The relatively long arms 22 then provide an elongated portion of the dart body rearwardly of the bow string or elastic member for grasping by the fingers and thumb, so as to properly orient the projectile prior to its release. The relatively wide rear portion of the groove permits the dart to escape from the bow string or the like without having this element engage the inner walls of the arm 22 defining the groove and thereby avoids deflection of the projectile from its intended flight. 50

While the invention has been described with reference to specific structural features, it is not intended that such disclosure should form the

metes and bounds of the invention. A number of modifications will suggest themselves to those skilled in the art, and such changes may be made without departing from the spirit and scope of the invention as set forth in the appended claims.

I claim:

1. A dart comprising, a dart body having a tapered nose portion, a pin extending forwardly from said portion, said dart body having an elongated groove therein extending throughout substantially two-thirds of the length of the dart body and provided with an open end at the rear thereof, and fins carried by the dart body and positioned upon the body to extend therefrom at opposite sides of said groove.

2. A dart comprising, a body member having a tapered nose, a pin extending forwardly from said nose, said body having a groove therein extending throughout the major portion of the length of the dart body and provided with an open end in the rear thereof, and said groove being wider at the aft open portion than at the forward end of the groove.

3. A projectile comprising, a dart body having a tapered nose portion, a pin extending forwardly from said portion, said dart body having an elongated slot therein extending throughout substantially two-thirds of the length of the dart body and provided with an open end in the rear thereof, said slot being wider at the rear end of the dart body than the width of the slot at the forward end of the slot, and fins carried by the dart outwardly of said slot.

4. A projectile comprising, a dart body having a tapered nose, a pin extending forwardly from said nose, said body having a slot therein extending throughout the major portion of the length of the dart body and provided with an open end in the aft portion, said groove being wider at the aft portion than at the forward end of the slot, and radially arranged fins mounted on the dart body rearwardly of the forward end of said slot.

5. A projectile comprising, a body member having a tapered nose, a pin extending forwardly from said portion, said body member having a slot therein extending throughout the major portion of the length of the body member to provide elongated arms on each side of said slot and having an open end at the aft portion, said slot being wider at the aft portion than at the forward end thereof, and two fins carried by each of said arms.
